UNITED STATES PATENT OFFICE.

GEORGE B. VON BODEN, OF SAN FRANCISCO, CALIFORNIA.

OIL-BURNER FEED AND HEATER.

1,299,069.

Specification of Letters Patent.

Patented Apr. 1, 1919.

Application filed March 27, 1918. Serial No. 225,033.

To all whom it may concern:

Be it known that I, GEORGE B. VON BODEN, a citizen of the United States, residing at the city and county of San Francisco and 5 State of California, have invented new and useful Improvements in Oil-Burner Feeds and Heaters, of which the following is a specification.

This invention relates to a conducting, 10 heating and distributing means for oil, which may be employed in conjunction with steam as a fuel in a burner, which is especially adapted for use in fire boxes of the type employed on locomotives.

15 It consists of an oil tank, having a heater located in the bottom, and connections whereby direct and indirect heat may be applied to the oil in such a manner as to prepare the oil for use in the burner.

20 It also includes details of construction which will be more fully explained by reference to the accompanying drawing, in which—

Figure 1 is a side elevation and partial 25 section of the device.

Fig. 2 is a plan view of the steam receiver and two distributing pipes.

As here illustrated, A is the rear portion 30 of a locomotive boiler and fire-box, within which is located an oil burner 2, of any suitable character, adapted to discharge a spray of oil into the fire-box where it is ignited. 35 3 is an oil tank which is located upon the tender 4 which occupies the usual position with relation to the engine boiler and fire-box.

In the bottom of the oil tank is a heating 40 box 3' and arranged within this box is a heating coil 5, through which steam may pass to heat the oil and render it suitable for use in the burner. A valve 6 may be opened by means of a bell-crank or suitable lever 7 and a connecting rod 8 within reach of the fireman who may thus control the supply of oil from the tank. 9 is a flexible hose or conductor, through which the oil may pass from the tank to a pipe 10 leading to the burner in the fire-box, and 11 is a superheater inclosing the pipe 10. A fountain or 45 manifold 12 is supplied with steam from the boiler and pipes lead from this fountain and deliver steam to the tank heater, the superheater, and to the burner.

The pipe marked *a* leads to the burner and 50 blow back, *b* carries steam to the steam passage of the burner, *c* carries steam to the

superheater which incloses the oil pipe leading to the burner, and *d* leads to a connection with the tank 3. By means of suitable cocks the various steam passages may be controlled 60 and the steam directed as required.

In the equipment of locomotives for burning heavy fuel oil, it is necessary to maintain a sufficiently high temperature to insure a free flow of the oil and also to provide 65 means for blowing out accumulations in the pipes and passages to insure satisfactory operation of the apparatus. By means of a pipe 14 steam is first admitted directly into the heating box containing the oil until the 70 oil is raised to a temperature of approximately 180°. This pipe may then be closed and the coil pipe at the bottom of the tank is supplied with steam through the pipe 13, and these steam pipes are controlled by suitable cocks so as to maintain the proper temperature. 75

Before starting the fire, the oil pipe 10, leading from the tank to the burner, should be cleansed of cold oil and accumulations, 80 and this is done by opening the valve 15^a which admits steam into the rear end of the pipe 10, thus blowing accumulations back into the tank and cleansing the pipe. A drain cock 15 is provided for releasing the 85 waters of condensation from the superheater casing 11. A cock 16 is then opened, admitting a jet of steam into the oil passage of the burner proper, thus cleaning it out in readiness for service. Everything being thus 90 in readiness, oil from the tank is admitted to flow through the pipe 10 into the receiver 17, from which it may pass into the oil passage of the burner while steam is admitted from the pipe *b* into the steam passage of 95 the burner to mingle with the oil in combustion within the fire-box. The coil in the oil-tank is freed from water which may condense in it, by means of a pipe 18 with a controlling cock 19. 100

It is to be particularly noted that the heating box 3' which is located within the main fuel tank 3 and communicates therewith through the valved passage 20, houses the heating coil 5 and also has the steam pipe 14 discharging directly therein. In starting up a cold locomotive, considerable time would be required to heat the whole body of very low gravity fuel in the tank to approximately 180° F. to cause it to flow through 110 the pipe connections, so to obviate this waste of time only a small portion of the fuel is

heated during the initial stages. This preliminary heating is expeditiously effected by opening pipe 14 to discharge steam directly into the heating box, the steam thoroughly heating the fuel in escaping therethrough. Continued heating of the fuel may then be carried on by means of the heating coil 5.

Having thus described my invention, what I claim and desire to secure by Letters Patent is—

1. The combination with a burner and a fuel tank for supplying oil thereto, of a heating box within the tank, a pipe connection between the heating box and the burner, means forming a communication between the heating box and the main fuel tank, valve means within the box to control the passages of said first means and pipe, and means for heating the oil contained in the heating box before it enters the pipe which delivers the oil to the burner.
2. An oil burning apparatus comprising an oil tank, a burner, a pipe connecting the tank and burner, a superheater for the pipe arranged adjacent the burner, and fluid pressure means connected to the pipe between the burner and superheater for cleaning the pipe by blowing the oil in the pipe back through the superheater into the tank.
3. An oil burning apparatus comprising an oil tank, a heating box arranged therein and communicating through its bottom therewith to receive oil therefrom, a burner connected to the heating box, and heating means arranged adjacent the bottom of the box and about its inlet.
4. The combination in an oil burning apparatus, of a burner, an oil supply main with an inclosing steam super-heater, a steam receiver connected with the main, and pipes leading from the receiver to the burner and to the rear of the oil main, an oil tank connected with the main, and direct and indirect heating means connected with the tank and operable independently of one another.
5. In an oil burning apparatus of the character described, a burner, an oil and a steam supply connected with the burner, an oil tank having a coil in the bottom, a pipe leading directly into the body of oil in the tank, an oil main contiguous to the burner,

a controlling valve in the tank, a steam super-heater surrounding the oil main, a fountain head upon the steam boiler, and valve-controlled pipes leading from said fountain to the burner, the super-heater, the rear of the oil main and to the direct and indirect heaters within the tank.

6. An oil burning apparatus including an oil tank, means to apply steam heat directly and indirectly to the tank contents, a burner consisting of superposed oil and steam passages discharging into the boiler fire-box, an oil main between the oil tank and the burner, a superheater surrounding the main, pipes connecting the boiler with the tank heating devices with the superheater and with the burner, and means connecting the superheater with the rear of the oil main and with the oil passage of the burner.

7. An oil burning apparatus including a burner having steam and oil conduits, an oil supply tank, an oil supply main connecting the burner to the tank, a superheater inclosing the main, a steam manifold, a pipe leading from the latter to the burner, a second pipe leading from the manifold to the superheater, a third pipe leading from the manifold to the oil supply main, and a fourth pipe leading from the manifold to the tank, said fourth pipe having branch terminals within the tank, one terminal opening directly therein and the other terminal defining a heating oil.

8. An oil burning apparatus comprising an oil tank, a heating box arranged therein and communicating through its bottom therewith to receive oil therefrom, a burner connected to the heating box, a steam heating coil arranged within the heating box and along its bottom to maintain the oil therein at a flowing temperature, and a steam pipe discharging into the heating box adjacent its bottom to preliminarily heat the oil therein.

In testimony whereof I have hereunto set my hand in the presence of two subscribing witnesses.

GEORGE B. VON BODEN.
